CLAIM

The ornamental design for an outdoor cooking utensil rack, as shown and described.

DESCRIPTION

FIG. 1 is a side view of the outdoor cooking utensil rack.
FIG. 2 is a top down view of the outdoor cooking utensil rack;
and,
FIG. 3 is a bottom up view of the outdoor cooking utensil
rack.
The outdoor cooking utensil rack can be used to store cooking
utensils in a convenient fashion near the outdoor cooking
station or grill.
